DWIGHT B. HILL, OF BRIDGEPORT, CONNECTICUT, ASSIGNOR TO BRIDGEPORT BEASS COMPANY, OF BRIDGEPORT, CONNECTICUT, A CORPORATION OF CONNECTICUT.

CARBURETER.

1,177,624.

Specification of Letters Patent.

Patented Apr. 4, 1916.

Application filed March 21, 1914. Serial No. 826,271.

To all whom it may concern:

Be it known that I, DWIGHT B. HILL, a citizen of the United States, residing at Bridgeport, county of Fairfield, and State 5 of Connecticut, have invented certain new and useful Improvements in Carbureters, of which the following is a full, clear, and exact description.

This invention relates to carbureters for 10 internal combustion motors, and more particularly to multiple jet carbureters, especially adapted for use on automobiles.

The primary object of the invention is the 15 provision of a carbureter having special means for vaporizing the gasolene, or other fuel, starting the motor, and in operation at low speeds.

More particularly, it is aimed to provide 20 means operative at low motor speeds to break up the liquid fuel mechanically in a very thorough manner, vaporize it very effectively, and supply the vapor to the motor, thereby avoiding all liability of stalling the motor. Furthermore, in my 25 improved carbureter, the auxiliary fuel jet, which supplies the motor at low speeds, is called into play, and put out of commission, automatically by actuation of the throttle valve in controlling the supply of fuel derived 30 from the main jet, and the carbureter as a whole is very simple, efficient, reliable and inexpensive.

To these and other ends, the invention 35 consists in the novel features and combinations of parts to be hereinafter described and claimed.

In the accompanying drawings, Figure 1 is a vertical section of a carbureter embodying my improvements, taken on line 40 1—1 of Fig. 2; Fig. 2 is a top plan view of the carbureter; Fig. 3 is an elevation of the carbureter, partly in section on line 3^a—3^a, and partly in section on line 3—3 of Fig. 1; Fig. 4 is a section on line 4—4 of Fig. 3; 45 and Fig. 5 is a detail of the mixing chamber wall and the fuel supply tube for the auxiliary jet.

Referring to the drawings, my improvements are illustrated as applied to a carbureter having a mixing chamber 10 in the form of an upright Venturi tube, which chamber is surrounded by a fuel reservoir 11, but it will be apparent from the following description that the invention can be 50 carried into effect in carbureters of other

types. In the form shown, the fuel reservoir or chamber 11 is provided with the usual float 12, the customary fuel inlet 13, and the ordinary float controlled inlet valve 14. At the upper end of the mixing chamber is a passage 15 adapted for communication with the customary inlet manifold (not shown), while the lower end of the mixing chamber is provided with an opening 16 in communication with the atmosphere. The air opening 16 is controlled by a valve 17, preferably of the butterfly type, as shown, and above said valve and in the constricted portion of the Venturi tube is the nozzle 18 for the main fuel jet. In the form shown, the main jet is supplied from a spray tube 19, inclined with respect to a vertical plane, and having its lower end 20 passing through the wall of the venturi, so as to communicate with the fuel chamber 21. The upper end 21 of the tube 19 is located in the most constricted part of the venturi, and the gasolene is maintained in the chamber 11 at about the level indicated by the line X—X, so that the level of gasolene in the tube 19 will be adjacent the upper extremity of said tube.

In the operation of the carbureter, a current of air is sucked upward through the venturi, carrying along with it a certain amount of the liquid fuel, e. g., gasolene from the upper end of the tube 19, and the amount of gasolene in the mixture is controlled by a needle valve 22, extending through the wall of the venturi into the discharge end 23 of the spray tube 19. This valve 22 may be provided with a duct 23, communicating with the atmosphere, and with the spray tube 19, for the purpose of promoting vaporization, and of preventing flooding at high speeds. The flow of the gas to the motor is controlled by a suitable throttle valve, and in the form shown, this throttle valve, indicated at 24, is of the butterfly type and located in the passage 15 leading from the upper end of the mixing chamber. The air inlet valve 17 and the throttle valve 24 may be operated by suitable means, well known in the art, which it is not necessary to illustrate.

In accordance with my present invention, I provide certain means for supplying an auxiliary spray of fuel to the outlet passage on the motor side of the throttle valve. In the form shown, the construction is as follows:

lows: In the passage 15, at a point above the throttle valve 24, in the closed position of said valve, is a spray tube 25, preferably arranged horizontally and slightly to one side of the axis of the throttle valve, as shown. This tube 25 extends at one end through the wall of the carbureter at the upper end of the latter, as shown at 26, and the duct or passage 27 of the tube communicates with the atmosphere at 28 at a point outside of the carbureter. The duct or passage 27 leads to a spray opening 29, located in the air passage controlled by the throttle valve 24, and so disposed as to direct upwardly into the inlet manifold a current of air passing laterally into the carbureter from the atmosphere through the duct 27. The spray opening 29 is also in communication with a gasoline duct 30, which is preferably of less diameter than the air duct 27, and in line with the latter duct and communicating therewith, so that currents of gasoline and air respectively may meet each other in the axis of the tube 25 at a point adjacent the spray opening 29, whereby the resulting mixture of air and gasoline may immediately pass out of such spray opening into the inlet manifold. The gasoline duct 30 may be controlled by an inlet valve 31, having an operating head 32, and lock nut 32^a, as shown in Fig. 3, whereby the supply of gasoline to the spray opening 29 may be regulated. The restricted portion of the duct 30 which is controlled by the needle valve forms in effect an auxiliary jet nozzle for the fuel. The gasoline passing through the duct 30 to the spray opening is derived from the main gasoline reservoir 11, for which purpose the tube 25 is connected with a depending pipe or tube 33, which dips at its lower end 34 into the gasoline in the reservoir 11 and communicates at its upper end with the gasoline duct 30, as shown in Fig. 3.

In ordinary carbureters, the vacuum in the mixing chamber, when starting, or when operating at low speeds, is frequently insufficient to vaporize the gasoline, or other fuel, particularly where the fuel is not of the best grade, which is often the case. The air inlet valve is of course closed to increase the vacuum in the mixing chamber, but in low speed operation much difficulty is encountered in breaking up the gasoline into small particles so that it will vaporize properly. In operating my improved carbureter, however, the throttle valve 24 is closed, or substantially closed, when starting, or when operating at low speeds, so as to cut off the fuel supply from the main jet 18. By closing the valve 24, the vacuum in the manifold is increased, and the only opening to the atmosphere is through the air duct 27, which is of quite restricted cross section as compared to the manifold. As a result, a thin but forcible current of air is sucked into the manifold, through the duct 27 and opening 29. Simultaneously, the vacuum in the manifold is communicated to the gasoline duct 30 (through the opening 29), so that a thin jet of gasoline is sucked up from the gasoline level, and through the duct 30, in opposition to the air current. The gasoline current and air current are exactly counter to each other, and they meet with considerable force adjacent the outlet 29, whereby the gasoline is very thoroughly broken up and atomized by the air and mixed with the latter in fine particles, so that after passing through the opening 29 in the form of a spray, the resulting mixture is in a condition to vaporize immediately and completely. Hence, by appropriately proportioning the cross sectional areas of the air and gasoline ducts respectively, and by properly controlling the gasoline duct, by means of the inlet valve 31, a mixture of suitable proportions and consistency may be delivered to the engine cylinders, even at the lowest speeds.

From the foregoing, it will be understood that the closing of the throttle valve, in augmenting the vacuum in the inlet manifold, and cutting off the main jet nozzle, causes the gasoline to be sucked into the manifold at a point on the motor side of the throttle valve, and at the same time creates a strong air jet, for the purpose of breaking up the gasoline mechanically in a very efficient manner, and of forming a mixture which will meet the required conditions. As the engine speed increases, the throttle valve will be opened, so that the vacuum will be communicated to the mixing chamber, and the main jet will be called into play. As the main jet is called into play, and as air is supplied through the ordinary air inlet 16, the suction at the spray opening 29 will decrease considerably, the pressure in the tube 25 being more nearly equalized with the atmosphere. As a result, the gasoline will no longer be sucked up through the tube 33, and the auxiliary jet will, for all practical purposes, cease to operate. However, at any time that the throttle is again closed, or partially closed, the auxiliary jet will again be brought into play automatically as a result of the increased vacuum on the motor side of the throttle valve.

In the particular form shown, the tube 25 at one end extends laterally through the wall of the outlet passage so that atmospheric air enters said passage as soon as such air passes through the open end of the tube; and the other open end of the tube 25, passing laterally through the wall of the outlet passage at another point, and communicating with the tube 33, enables the gasoline to pass directly into the outlet passage as soon as it flows through the end portion of the tube. In other words, the intermediate por-

tion of the tube is located in the outlet passage, and therefore the air and fuel reach said passage before they are intermixed. The specific construction adopted to obtain this result can be widely varied so long as means are provided for injecting fuel directly into the outlet passage in a comparatively undiluted state, and means are provided for injecting air directly into said outlet passage, said means being so constituted and arranged that the mixture of the air and fuel takes place in the outlet passage itself on the motor side of the throttle valve, rather than in a restricted passage or bypass leading to the main outlet passage. By my invention, the air and fuel are mixed together at the point where the pulverization of the fuel by the air will be most effective,—that is, in the main passage leading from the carbureter to the motor. So far as the broad aspects of the invention are concerned, the tube 25 can be replaced by another part or parts or arrangement which produce substantially the same broad result; and it is not essential that the currents of fuel and air conducted into the outlet passage be directed oppositely to each other so long as an initial mixture of said currents is effected in said passage on the motor side of the throttle. However, it is advantageous to use an arrangement or construction in which the fuel and air jets respectively are counter to each other at some appropriate point, so that the air jet will control the fuel jet and prevent flooding as the vacuum increases. It is a well known fact that if a source of air and a source of liquid are connected with means creating suction or partial vacuum, the amount of liquid flowing toward the vacuum source will tend to increase relatively to the amount of air as the vacuum increases, thus augmenting the richness of the mixture. By my improvements, the force of the air jet supplied to the outlet passage increases in proportion to the vacuum and, being exerted counter to the inflow of fuel, automatically preserves the same proportions of the mixture at varying pressures.

The foregoing description is necessarily a detailed one in so far as it concerns the particular embodiment of my invention selected for illustration and description, and I have not attempted to describe the numerous modifications in details of the device which may be adopted within the scope of the invention as defined in the claims.

What I claim is:

1. In a carbureter, the combination of a mixing chamber, a main jet nozzle therein, a fuel reservoir in communication with said jet nozzle, a passage leading from said mixing chamber, a throttle valve to control said passage, means to inject the fuel in said reservoir laterally into said passage at one

point, and means to inject air laterally into said passage at a substantially opposite point; substantially as described.

2. In a carbureter, the combination of a mixing chamber, a main jet nozzle therein, a fuel reservoir in communication with said nozzle, a passage leading from the top of said mixing chamber, a throttle valve above said nozzle to control said passage, an auxiliary jet nozzle in said passage above the throttle valve, having a supply tube dipping into the fuel reservoir, a regulating valve for said auxiliary jet nozzle, and means to conduct a current of air counter to the auxiliary fuel jet in said passage; substantially as described.

3. In a carbureter, the combination of a mixing chamber, a main jet nozzle therein, a fuel reservoir in communication with said jet nozzle, a throttle valve, a tube on the motor side of the throttle valve located in the passage leading to the motor, and having a spray opening, and means to conduct streams of air and fuel respectively to said spray opening; substantially as described. 90

4. In a carbureter, the combination of a mixing chamber, a main jet nozzle therein, a fuel reservoir in communication with said nozzle, a passage leading from the top of said mixing chamber, a throttle valve in said passage, a tube entering said passage at a point on the motor side of said throttle valve, and having a spray opening, and means to conduct opposing streams of fuel and air respectively to said spray opening; substantially as described.

5. In a carbureter, the combination of a main jet nozzle, a throttle valve, an outlet passage controlled by said valve, and inlets for fuel and air respectively leading laterally through the wall of said outlet passage on the motor side of the throttle valve, the fuel and air being drawn into said passage through the respective inlets by the suction of the motor, and said inlets so arranged that the fuel and air meet in said passage; substantially as described. 105

6. In a carbureter, the combination of a main jet nozzle, a throttle valve, an outlet passage controlled by said valve and leading to the motor, and inlets for fuel and air respectively passing laterally through the wall of said outlet passage on the motor side of the throttle valve and at substantially opposite points; substantially as described. 110 115

7. In a carbureter, the combination of a mixing chamber, an outlet passage leading therefrom, a main jet nozzle in said mixing chamber, a throttle valve to control said outlet passage, an auxiliary jet nozzle in the outlet passage on the motor side of the throttle valve, and means to create a current of air counter to the auxiliary fuel jet in the outlet passage; substantially as described. 125 130

8. In a carburetor, the combination of a mixing chamber, a main jet nozzle therein, an outlet passage leading from said mixing chamber, a throttle valve controlling said passage, an auxiliary jet nozzle for supplying a jet of fuel to the outlet passage at the motor side of the throttle valve, and means for creating a current of air in the outlet passage counter to the auxiliary fuel

jet so as to retard the flow of fuel from the auxiliary nozzle as the vacuum increases; substantially as described.

In witness whereof, I have hereunto set my hand on the 18th day of March, 1914.

DWIGHT B. HILL.
